AUTOMATIC SENSITIVITY CONTROL FOR SOUND ACTUATED DETECTION AND ALARM SYSTEMS
Howard M. Lerrick, 3105 Howard Ave. NW, Canton, Ohio, and Walter R. Brosch, 2032 Gregg Road, Akron 19, Ohio

Filed June 15, 1962, Ser. No. 202,763

1 Claim. (Cl. 340—261)

This application is a continuation-in-part of our co-pending U.S. application, Serial No. 4,791, filed January 26, 1960, now U.S. Patent No. 3,049,699.

The present invention relates generally to detection and alarm systems. More particularly, the present invention relates to alarm systems which are actuated by sounds or vibrations of a specific, predetermined amplitude. Specifically, the present invention relates to an alarm system which is capable of distinguishing between sounds of triggering amplitude created by environment and those created by intrusion.

Sound actuated detection and alarm systems respond to sound disturbances, referred to as intrusion sounds, which occur in the area or space under surveillance. Such sounds may result from glass breakage, pounding, jimmying, burning, etc. While it is desirable for the alarm system to be thus actuated by sounds of an unusual nature—i.e., of a predetermined amplitude—which are generally associated with disturbances resulting from the presence of unauthorized persons, it is equally as desirable for the detection alarm system to be nonresponsive to environmental sounds.

Prior known devices can be preset to remain unaffected by environmental sounds up to and including a predetermined amplitude, as, for example, the sound of motors, fans, or the like. However, these prior known sound-actuated devices have not been able to discern between sporadic environmental sounds of triggering amplitude and intrusion sounds.

For example, rooms, areas, buildings or warehouses required to be furnished with alarm devices are often located adjacent railroads, super highways or airports. The passing of a train, truck or airplane in proximity to the location under surveillance produces sound waves of sufficiently high amplitude and intensity to actuate the alarm system. To preset a sound actuated detection and alarm system to remain inactive to all sounds of the amplitude of these sporadic environmental sounds would render the system ineffectual to far too great a range of intrusion sounds.

It is therefore an object of the present invention to provide a sound-actuated detection and alarm system capable of distinguishing between sporadic environmental sounds of a far greater amplitude than required of intrusion sounds to actuate the system.

It is a further object of the present invention to provide a system as above which is not self triggered after once having been actuated.

It is a still further object of the present invention to provide an alarm system as above which may be set to give the operator an opportunity to leave the surveillance area without triggering the system.

These and other objects which will become apparent from the following specifications are accomplished by means hereinafter described and claimed.

2

One preferred embodiment of the present invention is shown by way of example in the accompanying drawings and described in detail without attempting to show all of the various modifications in which the invention might be embodied; the invention being measured by the appended claim and not by the details of the specification.

The drawing is a schematic wiring diagram of the operative circuits of a sound-actuated detection and alarm system according to the present invention.

In general, a detection and alarm system according to the present invention comprises a microphone, or sound pickup means, which feeds into an amplifier means. An energizing circuit is actuated by said amplifier means to trigger a signaling device.

An automatic sensitivity control circuit monitors the signal being fed to the energizing circuit and, if it is of sporadic environmental origin, blocks the system from being actuated in response to that sound.

An amplification control circuit also compatibly operates with the automatic sensitivity control circuit to negatively bias the amplifier in order to prevent echoes, or reverberations from the signaling device itself, from re-triggering the system, and to block impulses from triggering the signaling mechanism when setting the system in order to give the operator an opportunity to leave the area being guarded.

The alarm system, indicated generally by the numeral 10, may be self-contained in an enclosing case, indicated in schematic outline 11, which is portable for moving about from place to place and which need only be connected to the usual alternating current service line, or, as will be seen, the system is readily adaptable as a fixed installation.

A microphone, or suitable transducer means 12, generates electrical signals in response to sound waves in the room or space under surveillance. The signals from the microphone pass through a filter 14 and are amplified by an amplifier 15. The amplified signals are fed from the output of the amplifier to a control apparatus 16, which, when the signals are of sufficient amplitude, acts to energize a loud speaker or other signaling device 17. Signals from additional or substitute sensing devices may be fed to the filter 14 through jacks J1 or J2 and auxiliary audible or visual signaling devices, sirens, blinkers and the like may be connected to the terminal leads A1 and A2.

The filter 14 functions to emphasize certain sound frequencies or to de-emphasize others, so that the alarm device may be made more or less responsive to certain types of intrusion sounds. The filter 14 may be omitted where such specific response is not required, as it constitutes no part of the automatic sensitivity control circuit of the present invention.

The amplifier 15 comprises a tube V1 connected as a grounded grid amplifier and having the output of the filter 14 connected to the cathode 19. Tubes V2, V3 and V4 are connected in grounded cathode amplifier stages, arranged in cascade, with the input of the tube V2 taken from the plate of the tube V1 through the capacitor 20. The circuits of the tubes V1, V2 and V3 are generally conventional, except that the grid returns of the tubes V2 and V3, through the resistors 21 and 22, are made to an automatic sensitivity control circuit and also to an amplification control circuit, the latter of which includes

resistor 23, capacitor 24 and capacitor 25, and which applies the negative bias on the amplifier to render the amplifier insensitive to signals from the microphone for a predetermined interval immediately after setting the device and immediately after the device has been actuated by an intrusion sound.

Direct current voltages are supplied to the amplifier 15 and to the control circuit 16 through a positive line 26 and a negative common line 27. The lines 26 and 27 are connected to a rectifier-filter supply (not shown in the diagram) incorporated in the enclosure 11. A resistor-capacitor filter 28 provides additional filtering, desirable for the amplifier stages which include the tubes V1 and V2.

The control circuit 16 comprises a grid-controlled gas discharge tube T1, an alarm relay R1, and a time delay relay R2, all connected in series between the lines 26 and 27. The output of the amplifier 15 is coupled to the control grid 29 of the gas tube T1 through a capacitor 30, and the control grid circuit is returned to the negative line 27 through a grid resistor 31. A cathode resistor 32 establishes a positive bias on the cathode 33 of the gas tube T1 and hence establishes the amplitude of signal voltage which must be applied to the control grid 29 to fire the tube T1. The cathode 33 and plate 34 of the tube T1 constitute a series circuit with the resistor 32 and relays R1 and R2.

The alarm relay R1 has normally-open contacts 37 thereof connected in a series circuit which includes terminal leads L1 and L2 and parallel branches comprising a loudspeaker 17 and series switch S1, the indicator lamp 36, and terminal leads A1 and A2 (referred to, either generally or separately, as an alarm circuit), and another parallel branch including the time delay relay R2 and a variable resistor 38 (referred to as a reset circuit). When the tube T1 fires, the alarm relay R1 is energized and the contacts 37 are closed to activate the alarm circuit. With the terminal leads connected to an alternating current line, activation of the alarm circuit will cause the loudspeaker 17 to be sounded. In testing or setting the alarm device, the switch S1 is opened and the indicator lamp 36 is observed to determine the operability of the device.

The time delay relay R2 functions to open the plate circuit of the gas tube T1 after the lapse of a predetermined interval of time following the firing of the tube T1 and activation of the alarm circuit. Thus, when the contacts 37 are closed, relay R2 is energized from the power line (through the terminal leads L1 and L2) and, following the delay interval, the closed contacts of relay R2 are opened by thermal expansion. Accordingly, the relay R1 is de-energized and the alarm circuits deactivated by opening of contacts 37. Simultaneously therewith, the relay R2 becomes de-energized and, since interruption of the series circuit causes the gas tube T1 to de-ionize, the circuit remains open until the gas tube T1 is again fired by an alarm signal of sufficient amplitude.

The relay R2 is a thermal time delay relay of known design and the variable resistor 38 provides adjustment of the delay interval to the desired predetermined time. Delay intervals of 30 seconds are useful in many applications of the device and the other known delay devices may be utilized to obtain greater delay intervals or to provide other adjustment means.

The terminal leads L1 and L2 are referred to as an energizing circuit, e.g., for the loudspeaker 17, the indicator lamp 36 or an auxiliary signaling device connected to the terminal leads A1 and A2. As so used, the term may or may not include the energizing source, to which the leads L1 and L2 are intended to be connected.

The amplification control circuit, e.g. resistor 23, capacitor 24, and capacitor 25, functions to impress a high

negative bias upon the control grids of tubes V2 and V3 during an interval following the sounding of the loudspeaker. Thus the cathode 33 of the gas tube T1 has a small positive bias voltage, determined by the resistor 32 and resistors 39 and 40, when the tube is not conducting. However, when tube T1 fires, the voltage of the cathode 33 increases to a relatively high positive value and the capacitor 25 charges to that voltage (through the resistor 23). Then, when tube T1 again becomes non-conducting due to the opening of the contacts 37 and the cathode 33 returns to its original voltage, the voltage across the capacitor 25 is impressed, as a high negative bias, upon the control grids of tubes V2 and V3. The high negative bias effectively blocks the amplifier stages so that the tube T1 cannot again be fired by signals from the microphone 12 during the interval when the bias is applied.

The negative bias is applied to the grids of tubes V2 and V3 substantially throughout the time interval required to discharge the capacitor 25 through the resistors 23 and 32 and into the capacitor 24. The value of resistor 23 is chosen so that the time required to discharge capacitor 25 and bring the voltage across the resistor 23 and capacitor 24 to the normal operating level inactivates the amplifier for the desired interval following the cessation of the alarm. In the embodiment of the invention described herein the cathode bias voltages were 8 volts and 98 volts; resistor 32, 10,000 ohms; capacitor 25, 4 mfd.; resistor 23, 1 megohm; capacitor 24, 1 mfd.; and the discharge time was between 15 and 30 seconds. Accordingly, the amplifier 15 was inactive and the device did not respond to sounds, which would otherwise fire tube T1, for an interval of from 15 to 30 seconds following cessation of sounding of the speaker.

The advantages of the arrangement will be apparent. The device is made insensitive to echoes and vibrations caused by the loudspeaker and self-retirpping is prevented with a simple and efficient control circuit 16.

The alarm device includes a test circuit for determining the performance or operability of the device, either during installation or at any time thereafter. To this end a test switch S2 has a normally closed contact 41 connected in the series cathode circuit of the gas tube T1 and does not affect the operation of that circuit. A normally open contact 42 is connected to the cathode 33 through a series resistor 43 such that, when the test switch is depressed, the resistor 43 is connected to the positive line 26 and the cathode 33 is energized to the same positive voltage that it acquires when the tube T1 fires in the ordinary operation of the control circuit, e.g., in the exemplary case, 98 volts. Upon release of the test switch, the voltage across the capacitor 25 is applied to inactivate the amplifier 15. With this arrangement, the amplification control circuit may be tested at will and, further, the alarm device may be inactivated for a time sufficient to permit the user to leave the room without tripping the alarm, after the device has been set.

A potentiometer 44 in the grid circuit of tube V4 enables adjustment of the amplifier 15 to accommodate ambient noise in the space under surveillance and permits adjustment of the device to determine the magnitude of sound disturbance which will actuate the alarm.

The automatic sensitivity control circuit, indicated generally by the numeral 60, functions to monitor the signal leaving the amplifier 15 to determine if the nature of its origin is environmental or intrusion.

The output signal leaving the amplifier 15 is taken off at the plate 61 of tube V4, by-passed through capacitor 62 in series with the winding 63 of potentiometer 64 to the negative common line 27. The grid or base connection 65 of tube, or amplifying means, V5 is connected to the variable or center tap 66 of potentiometer 64. The cathode or emitter side 68 of tube V5 is connected to the negative common line 27 through resistor 69. The plate,

collector, or output 70 of tube V5 is connected to the positive line 26 through resistor 71. The plate or output 70 of tube V5 is also coupled to the cathode or emitter side 72 of diode tube or rectifying means V6 through capacitor 73. The cathode 72 of diode tube V6 is also connected to one side of a resistor 74, and the other side of resistor 74 is connected to the negative common line 27.

The plate, collector, or output 75 of tube V6 is connected to one side of a resistor 76. The other side of resistor 76 is connected to the negative common line 27. The plate 75 of tube V6 is also connected to one side of capacitor 78. The other side of capacitor 78 is also connected to the negative common line 27. The plate 75 of tube V6 is further connected to one side of resistor 79. The other side of resistor 79 is connected through capacitor 80 to the negative common line 27 and is also connected to one side of another resistor 81. The second side of resistor 81 is connected to one side of a capacitor 82 and also to the grid feedbacks of tubes V2 and V3 in amplifier 15 through resistors 21 and 22, respectively. The second side of capacitor 82 is connected to the negative common line 27.

While it is theoretically possible for the automatic sensitivity control (hereinafter referred to as ASC) circuit 60 to monitor the signal at the plate of any of the tubes in the cascade amplifier circuit, it is more practical to monitor the signal as it leaves the last stage of the amplification in order to have the greatest signal strength available for operation of the ASC circuit.

The sensitivity of the ASC circuit 60 can be preset through the variable resistance of potentiometer 64, thus controlling the gain of the system through the grid voltage applied to tube V5. The tube V5 amplifies the signal received which passes through the rectifying tube V6, thus assuring that a negative voltage is always presented through the network of capacitors 78, 80 and 82, and resistors 76, 79 and 81. This network of capacitors and resistors provides a time delay barrier for the negative voltage leaving tube V6 before it is impressed as a negative bias on the grid returns of tubes V2 and V3 of the amplifier means 15.

In operation, the energizing circuit of the sound detection and alarm system requires the application of approximately six volts to the grid of the gas tube T1 to fire tube T1 and actuate the signaling means. Thus, if an intrusion sound is sufficient to create an impulse of six volts to the grid of tube T1 the alarm will be actuated.

However, let us suppose that a sporadic intrusion sound is detected by the system, as, for example, the approach of a train. It is apparent when the train is initially heard, the amplitude of the sound at the sound pickup location of the alarm system, will not be sufficient to trigger the device, but will gradually or progressively increase in amplitude to a point which would be sufficient to trigger the device. The electrical signal initiated by the sound of the train is monitored by the ASC circuit, and, because of the time delay feature of the ASC, will impress a negative bias on to the amplification circuit at a fixed interval of time after having been monitored.

A resistor 83 is connected between the capacitor 25 of the amplification control circuit and the ASC circuit to provide a high impedance to the biasing current of the ASC. In the embodiment shown, the use of a resistor 83 having a resistance of 560,000 ohms provides sufficient impedance to the ASC circuit and yet allows a fifteen second bias of the amplification circuit by the amplification control circuit.

Thus, the electrical signal resulting from an intrusion sound, such as the breaking of glass, or the like, will, because of the time delay in the ASC, fire tube T1 before the ASC biases the amplification circuit; whereas, a sound which progressively reaches the same amplitude will have warned the system of its impending arrival, permitting the ASC to have biased the amplifier circuit sufficiently to

prevent the electrical signal resulting from the sporadic environmental sounds from firing the gas tube T1 when the sound reaches triggering amplitude.

The time delay of the system can be varied by the value of the capacitors and resistors used in the time delay network, and it has been found that a delay of a few thousandths of a second is sufficient and is effected by employing 220,000 ohm resistors 79 and 81, 560,000 ohm resistor 76, and 0.1 mfd. capacitors 78, 80 and 82.

10 The values of the remaining resistors and capacitors used in the preferred embodiment of the ASC circuit are as follows: Cathode resistor 69, 560 ohms; cathode resistor 74, 560,000 ohms; plate to positive line resistor 71, 100,000 ohms; and capacitors 62 and 73, both 0.001 mfd.

15 The use of a 500,000 ohm potentiometer 64 in series with a 0.001 mfd. capacitor 62 not only controls the gain of the ASC circuit 60 but also prevents draining the signal leaving the amplifier completely away from the energizing circuit.

20 When the biasing voltage of the ASC circuit is impressed upon the grid returns of tubes V2 and V3, the voltage at the grid of gas tube T1 can be maintained at, say, a 5 volt level (i.e., one volt below firing) for any given environmental sound. It should be noted that even 25 in the event that an intrusion sound occurs simultaneously with the environmental sound, the superimposed intrusion sound will increase the grid voltage of gas tube T1 to fire before the ASC can compensate for the increased signal leaving the amplifier.

30 Superimposed environmental sounds, however, will not actuate the system because the bias impressed by the ASC circuit will be increased proportionately to prevent the grid voltage on gas tube T1 from reaching firing potential. Thus, even if the train should blow its whistle, which, 35 incidentally, emits a sound of gradually increasing amplitude, as it passes the surveillance area, the detection and alarm system will not be actuated.

It has also been found that if the detection and alarm system is in a building the ASC circuit will differentiate 40 between sounds on the building walls and those exterior thereof. That is, if a bolt of lightning strikes exteriorly of the building, the sound dampening or attenuating barrier of the building itself will be sufficient to permit the ASC to operate and prevent actuation of the alarm.

45 It is, therefore, apparent that a sound actuated detection and alarm system constructed in accordance with the concept herein disclosed accomplishes the objects of the invention.

What is claimed is:

50 In a sound actuated detection and alarm device having sound pickup means, first amplifier means having the input thereof connected to said sound pickup means, at least one signaling device and an energizing circuit actuated by said first amplifier means for triggering said signaling device, said energizing circuit having thermal delay de-actuating means and amplification control time delay feedback means, the improvement comprising; second amplifier means having the grid control input thereof connected to the output of said first amplifier means through 55 a potentiometer having a resistance of on the order of 500,000 ohms to prevent excessive draining of the signal from said first amplifier means, rectifier means connected to the output of said second amplifier means, a time-delay network connecting said rectifier means to said first amplifier means ahead of the output thereof to impress 60 a negative blocking bias thereto delayed by a few milliseconds to prevent said first amplifier means from triggering said energizing circuit in response to environmental sounds, and a high impedance blocking means connected between said time-delay network and said amplification control time-delay feedback means to prevent impressing signals from said time-delay network on said energizing circuit.
